DESIGN FOR A HOSE COUPLING

Lester A. Carlson, Pittsburgh, Pa., assignor to
Sevill Manufacturing Company, Waterbury,
Conn., a corporation of Connecticut

Application March 5, 1941, Serial No. 99,362

Term of patent 14 years

To all whom it may concern:

Be it known that I, Lester A. Carlson, a citizen
of the United States, residing at Pittsburgh,
county of Allegheny, State of Pennsylvania, have
invented a new, original, and ornamental Design
for Hose Couplings, of which the following is a
specification, reference being had to the accom-
panying drawing, forming part thereof.

Fig. 1 is a side elevational view of a hose cou-
pling embodying my new design, and

Fig. 2 is a top plan view of the same.

I claim:

The ornamental design for a hose coupling,
substantially as shown.

LESTER A. CARLSON.
